FASTENING FOR SUITCASES AND THE LIKE

Charles William Cheney, Soho, Birmingham,
EnglandApplication January 5, 1937, Serial No. 119,071
In Great Britain February 1, 1936

2 Claims. (Cl. 70—74)

This invention relates to improvements in key-locked fastening means for brief cases, suit cases and other similar types of hand baggage, and has reference particularly to a fastening means 5 of the type embodying a slideable bolt, which is retracted against the action of a spring by means of a hand-operated knob, and which is generally mounted in a plate attached to the body portion of the case, and a hinged member carried by the 10 lid or closure of the case and provided with a staple or notched peg adapted to be releasably engaged by the bolt.

The object of this invention is to provide a key-locked fastening means of this character, 15 which combines the slideable bolt with other novel features to produce an efficient arrangement capable of being manufactured very cheaply in production.

Briefly the present invention consists of a casing comprising two substantially flat metal plates, one thereof being the front plate and having its 20 wall pierced, the other member forming the back plate and being provided with a depressed area carrying a pivot peg for a tumbler. The two plates are rigidly connected to each other to form the said casing. A slideable bolt is formed by a dished plate which is adapted to lie flush with, and slide within, the recess of the back plate, its 25 surface being formed with a locking and releasing slot. The tumbler is a flat plate formed with a stump, and with means for engagement with the bit of a key, and is adapted to be revolvably applied to the pivoting peg of the back plate to lie and work within the dished portion of the 30 bolt. The spring lies within the dished formation of the bolt, and is a double limbed one operative between the edge of the tumbler and a forward edge of the bolt. The key peg to support the key is arranged so that its bit co-operates with the tumbler. The hand operated knob 35 is applied against the face of the casing and connects with the bolt.

In the accompanying drawings, I have illustratively exemplified two embodiments of my invention.

Fig. 1 is a longitudinal section through the assembled fastening member.

Fig. 2 is a plan of Fig. 1 with the front plate removed and the slideable bolt in fastening position.

Fig. 3 is a similar plan to Fig. 2 but with the slideable bolt retracted.

Fig. 4 is a longitudinal section, and

Fig. 5 is a transverse section of the slideable bolt 55 separately.

Fig. 6 is a side elevation of the tumbler separately.

Fig. 7 is a longitudinal section of the back plate separately.

Fig. 8 is a plan of a modified form. 5

In all the figures of the drawings the same letters of reference are used where permissible to indicate corresponding parts.

In Figs. 1-7, the casing of the fastening member embodies the front plate *a* and the back plate *c* rigidly connected to constitute a one-piece casing.

The front plate has a right-angled boundary flange *a* giving depth to said plate, and is pierced through its face at *a* and at *a* for purposes 15 hereinafter made clear.

The back plate *c*, shown separately in Fig. 7, has a boundary right-angled flange *c* giving this plate depth, and at the corners is provided with prongs *c* for use in the attachment of 20 this plate, and consequently the fastening member, to the attaché case, and particularly this back plate is provided with a surface recess *c* and with a pivoting peg *c*, the latter shaped out from the metal of the bottom of the recess. 25 This back plate is also fitted with a key peg *c*, and with certain stops and piercings as will be hereinafter described.

The front plate *a* and the back plate *c* fit coincidentally together the one within the other, and 30 are rigidly secured by clinchings at the parts *d*, *e*, *f* and *g* as clearly shown in Figs. 1, 2 and 3. When so secured the surface recess *c* is immediately at the back of the front wall of the front plate as clearly shown in Fig. 1. 35

The slideable bolt *h* is of dished cross-section clearly shown at *h* Figs. 4 and 5, the depth of the dishing being such as to allow said bolt to workably lie within the surface recess *c* of the casing. Said dishing is at the nose *h* and at 40 the sides *h*, but the back *h* of said bolt is left open, or substantially so. Said bolt is formed with a locking and releasing slot *h*, and with a pierced-out stop *h*.

The tumbler *i* is plate-like and formed with a 45 stump *i* and with a notch *i* for co-operation with the bit of the key, and is also shaped at *i* for co-operation with the one arm *j* of a spring *j* serving as bolt spring and tumbler spring, the other arm *j* of this spring working against the 50 forward edge of the dished bolt *h*. The tumbler *i* and the spring *j* both lie workably within the dished formation of the bolt *h*, the tumbler *i* being revolvably applied to the pivoting peg, *c*, of the back plate, *c*, so that its stump *i* works 55

within the locking and releasing slot $h6$ of said bolt.

The back plate has formed from it a stop $c7$ to limit the swing of the tumbler in both directions as will be clearly seen from Figs. 2, 3, and 7, and is formed with piercings $c8$, $c9$. The piercing $c8$ accommodates the staple on the other fastening member to be engaged by the nose of the bolt as hereinbefore referred to, this piercing to be used for clinching the front and back plates to each other. The piercing $c9$ serves for said clinching and for clearance in the fitting of a hand-operated knob k slidably and revolvably applied to the face of the front plate.

Said knob k has a shank $k2$ passing freely through the piercing $a4$ and engaging in a circular hole $k3$ in the bolt h to revolve therein, this shank having rigidly attached to it inwards of the bolt h a partly revolvable plate l to revolve and slide with said knob and constitute a catch plate to the bolt h to secure said bolt in fastening position without keylocking it. The position shown in the drawings of the catch plate l is one leaving the bolt free to be drawn back from the knob as represented in Fig. 3, the knob, bolt and catch plate sliding as one-piece. If the knob k is revolved a quarter of a turn, in the hole $k3$ of the bolt as a bearing, the catch plate l revolves with it and its cam edge $l2$ abuts against the clinching lug f of the casing, so that now the bolt cannot be withdrawn from the knob although it is not key-locked. If the spring j should break at any time this cam-like catch plate l can serve to move the bolt h into fastening position and secure it there quite independent of the key action. The revolution of the cam plate l is limited in either direction by the stop $h7$ shaped out from the bolt h , and clearly shown in Figs. 2, 3 and 5.

Figs. 1 and 2 show the bolt in key-locked position the stump $i2$ of the tumbler engaging a forward edge of the slot $h6$.

Fig. 3 shows the tumbler in unlocking position and the bolt h retracted, the stump $i2$ being free in that part of the slot $h6$ parallel with the bolt.

It will be clear that the key engages the key peg $c6$ and that its bit co-acts with the notch $i3$ of the tumbler.

In the modified form shown in Fig. 8 the key peg $c16$ is disposed on the bolt, and the tumbler $i10$ pivoted on the peg $c15$ carries besides the stump $i12$ projecting into the slot $h16$ two additional stumps m and n to co-operate with the bit of a key. The remaining parts are arranged sub-

stantially as described with reference to Figs. 1-7, with the difference that in the construction according to Fig. 8 the catch plate l and the co-operative members are omitted and the knob is clinched to the bolt $h10$ by the lugs o and r , so as to be not rotatable, but only slidably with the bolt.

Having now described my invention, what I claim and desire to secure by Letters Patent is:—

1. In a keylocked fastening member of the kind described, the combination of a casing comprising a front plate and a back plate, the latter having a depressed area and carrying a pivot peg; means for rigidly connecting said front and back plates to one another, a bolt of dished form slidably disposed within said depressed area of the back plate and being provided with a locking and releasing slot; a tumbler rotatably mounted on said pivot peg within the depression of said bolt, said tumbler having a stump to co-operate with the locking and releasing slot of said bolt, and means to be engaged by the bit of a key; a key peg to support a key in engaging position relative to the tumbler; spring means in the casing to act upon said bolt and said tumbler, said spring means being disposed within the depression of the bolt; and a knob on the outer face of the front plate of the casing and connected with said bolt through an opening of said front plate.

2. In a keylocked fastening member of the kind described, the combination of a casing comprising a front plate having a rectangular boundary flange and a back plate having a rectangular boundary flange, a depressed area in its face, and fixed on said face a pivot peg; means for rigidly connecting said front and back plates to one another; a bolt of dished form slidably disposed within said depressed area of the back plate and being provided with a locking and releasing slot; a tumbler rotatably mounted on said pivot peg within the depression of said bolt said tumbler having a stump to co-operate with the locking and releasing slot of said bolt and a notch to be engaged by the bit of a key; a key peg rigidly carried by said back plate to support a key in engaging position relative to the notch of the tumbler; a spring in the casing to act upon said bolt and said tumbler, said spring being disposed within the depression of the bolt; and a knob on the outer face of the front plate of the casing and connected with said bolt through an opening of said front plate.

CHARLES WILLIAM CHENEY.
